ADVERTISING CHANGE TRAY

Rafael Lan, New York, N. Y., assignor to Advertising Change Tray, Inc., a corporation of New Jersey

Application August 12, 1939, Serial No. 289,723

2 Claims. (Cl. 133—14)

This invention relates to new and useful improvements in an advertising change tray.

The invention has for an object the construction of an article as mentioned which is characterized by a base member having a cupped area at its front end, a flanged tray for holding change and hingedly mounted on said base member and adapted to be tilted upwards at its rear end to discharge its change into the cupped area. Furthermore the invention proposes to construct the tray so that its rear end is opened, and it is proposed to provide this rear end with a rearwardly and downwardly extending ledge over which the change on the tray may be brushed backwards into one's hand placed beneath the ledge.

Still further the invention contemplates the use of flat elements mounted upon the tray and one of which is to be imprinted with advertising material, and a novel arrangement for holding these flat elements removable in position.

Still further the invention proposes an arrangement whereby the tray is normally urged into an upwards tilted position, and a means is proposed for holding the tray normally in a horizontal position.

Still further the invention proposes the construction of an article as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an advertising change tray constructed in accordance with this invention.

Fig. 2 is a perspective view of the tray shown in Fig. 1 but viewed from the front.

Fig. 3 is a perspective view of the advertising change tray, and the tray thereof being pivoted upwards to spill the change into the cupped area.

Fig. 4 is a perspective view illustrating the manner in which the change is removed from the cupped area.

Fig. 5 is a rear elevational view of the advertising tray with the tray element thereof in its raised position.

Fig. 6 is a longitudinal vertical sectional view of the tray as illustrated in Fig. 2.

Fig. 7 is a fragmentary elevational view looking in the direction of the line 7—7 of Fig. 1.

Fig. 8 is a fragmentary plan view looking in the direction of the line 8—8 of Fig. 7.

Fig. 9 is a longitudinal vertical sectional view of an advertising change tray constructed in accordance with a modification of this invention.

Fig. 10 is a fragmentary vertical sectional view taken on the line 10—10 of Fig. 9.

Fig. 11 is a fragmentary horizontal sectional view taken on the line 11—11 of Fig. 10.

Fig. 12 is a fragmentary vertical sectional view 10 taken on the line 12—12 of Fig. 11.

The advertising change tray in accordance with this invention includes a base member 10 having a cupped area 11 at its front end. A flanged tray 12 for holding change 13 is hingedly mounted on the base member 10 and is formed with an open front area 14. The flanged tray comprises a base section 12^a which is surrounded by flanges 12^b along the side edges. At the open front 14, the tray is devoid of flange material.

A means is provided for pivotally mounting the tray and supporting the tray in a normal horizontal position, so that it may be tilted upwards, at its rear end to discharge its change 13 into the cupped area 11. This means includes a pair of lugs 15 formed upon the bottom face of the tray 12 and pivotally connected by a bolt 16 with lugs 17 formed upon the top face of the base member 10, and an arrangement for limiting the amplitude of pivoting. The bolt 16 is provided with a knurled head 16^a and with a knurled threadedly mounted nut 16^b engaged on the other end. The nut may be removed when desired and then the bolt may be withdrawn and the tray removed from the base member. There are several reinforcing ribs 18 formed upon the bottom of the tray for reinforcing it.

The tray 12 has its rear end 19 opened, and this rear end is provided with a rearwardly and downwardly extending ledge 20 over which the change on the tray may be brushed backwards into one's hand 21 placed beneath the ledge. In Fig. 1 a hand 22 is schematically illustrated brushing the change 13 rearwards so that it may fall into the hand 21 also schematically shown.

A projection 23 is formed upon the top of the base member 10 and this projection supports a rubber element 23 or other cushion or pad element. Another projection 25 is formed upon the bottom of the tray 12 and normally rests on the cushion 24. In this position of the parts the tray 12 is in a horizontal position. The sides of the tray 12 are somewhat curved, with flanges 12^b extending along its curved sides. Flat elements 26 and 27 are rested upon the tray 12 and have 55

their sides cut so as to extend along the flanges 12^b. The flat element 26 may comprise a sheet of printed material displaying advertising matter. The flat element 27 comprises a sheet of glass or other transparent material rested upon the advertising material 26 and through which the advertising material may be viewed. A means is provided for releasably holding the flat elements 26 and 27 in position.

10 The holding means mentioned in the latter portion of the previous paragraph includes a pair of leaf springs 28 mounted upon the flanges 12^b of the tray. Each leaf spring 28 is fixedly mounted at one of its ends by rivets 29. Each leaf spring 28 has an intermediate portion 28^a which extends through an opening 30 in the adjacent flange 12^b. These intermediate portions extend over the edges of the top flat element 27. Each leaf spring has its free end 28^b extended for a short distance along the outside face of the adjacent flange 12^b so that it may be manually gripped with one's finger nail to pull the spring to disengage the intermediate portion from its position over the flat elements. Thus the flat elements are free and may be lifted and removed from their positions.

15 The operation of the device is as follows:

20 The advertising change tray is rested upon a counter so that the cupped area 11 extends to the front of the counter towards the customer. The cashier in giving change first places the change upon the top element 27 on the tray 12. Since the tray is now horizontal it is an easy matter to inspect and count the change. If the change is incorrect the cashier may brush it rearwards over the ledge 29 with one hand, back to the other hand. If the change is satisfactory the cashier lifts the rear end of the tray 12 upwards as illustrated in Fig. 3 so as to spill the change into the cupped area 11. From this area the customer reaches over with one hand as illustrated in Fig. 4 and removes the change. When the tray 12 is released it will move downwards under the action of gravity and since the bolt 16 is located towards the front of the tray it will come to a position of rest with the projection 25 resting upon the pad 24.

25

30 The tray 12 and base member 10 are preferably formed from Bakelite or other composition material in a suitable mould. If desired the underside of the base member may be filled with material 32 which may be plaster, lead, or other suitable material. Several rubber feet 33 are mounted along the edges of the bottom edge of the base member 10 by which the same may be rested on a counter.

35 In Figs. 9 to 12 inclusive, a modified form of the invention has been disclosed which distinguishes from the prior form in the fact that a means has been provided for automatically tilting upwards the tray 12 to spill its change into the cupped area 11 when this is desired. This means includes a spring 35 coaxially mounted on a bolt 16' which is used to pivotally connect the tray 12 with the base member 10. This spring 35 has one of its ends 35^a engaging against the tray 12 and its other end 35^b engaged against one of the brackets 17' of the base member.

40 The base member is provided with a pair of brackets 17' through which the bolt 16' passes. These brackets 17' are formed with circular openings 36 through which the bolt rotatively passes. The bolt 16' also engages through lugs 15' formed upon the bottom of the tray. However these lugs 45 are formed with non-circular openings through

which the bolt 16' non-rotatively passes. For example the bolt 16' is illustrated as square in transverse cross section and the openings in the lugs 15' are of similar shape.

45 The bolt 16' is urged longitudinally in one direction by a spring 38 coaxially mounted on one end thereof and acting between one of the brackets 17' and the nut 16^b upon the end of the bolt. The head 16^a of the bolt is formed with a cutout 39 normally engaged by a tooth 40 formed on the side of the adjacent bracket 17'. This tooth 40 and cutout 39 holds the bolt 16' from turning and so the tray 12 is locked in its horizontal position.

50 However the tray 12 may be tilted upwards at its rear end by manually pressing inwardly the nut 16^b so as to shift the bolt 16' longitudinally to disengage the cutout 39 from the tooth 40.

55 Then the spring 35 is free to pivot the tray 12 so that its rear end pivots upwards and the tray 20 spills its change into the cupped area 11. The tray may be replaced to its horizontal position by merely pivoting it downwards. When it reaches a horizontal position the spring 38 will automatically move the bolt 16' so that the cutout 39 again engages the tooth 40. Then the tray is locked in the horizontal position and is ready to dispense change again.

60 In this form of the invention the base member 10 is shown hollow. It is not filled with any material as illustrated in the form of the invention shown in Fig. 6.

65 While I have illustrated and described the preferred embodiments of my invention, it is to be understood that I do not limit myself to the precise constructions herein disclosed and the right is reserved to all changes and modifications coming within the scope of the invention as defined in the appended claims.

70 Having thus described my invention, what I claim as new, and desire to secure by United States Letters Patent is:

75 1. In an advertising change tray, a base member, a flanged tray for holding change and pivotally mounted on said base member and having an open front area, and means for supporting said tray in a horizontal position so that it may be tilted upwards at its rear end to discharge the change through said open front area, said pivotal mounting comprising a pair of spaced brackets extending upwards from said base, a pair of spaced lugs extending downwards from the bottom face of said tray and overlapping the top end of said brackets, a bolt extended through said overlapping portions of said brackets and lugs, and means for urging said tray into a tilted position with its rear end extended upwards, said bolt being slidably extended through said brackets and lugs and having squared areas extended through squared openings formed in said lugs for locking said bolt to said lugs to turn said bolt when said tray tilts, and means for locking said bolt to one of said brackets for holding said bolt in a position in which said tray will be horizontal.

80 2. In an advertising change tray, a base member, a flanged tray for holding change and pivotally mounted on said base member and having an open front area, and means for supporting said tray in a horizontal position so that it may be tilted upwards at its rear end to discharge the change through said open front area, said pivotal mounting comprising a pair of spaced brackets extending upwards from said base, a pair of spaced lugs extending downwards from

the bottom face of said tray and overlapping the top end of said brackets, a bolt extended through said overlapping portions of said brackets and lugs, and means for urging said tray into a tilted position with its rear end extended upwards, 5 said bolt being slidably extended through said brackets and lugs and having squared areas extended through squared openings formed in said lugs for locking said bolt to said lugs to turn said bolt when said tray tilts, and means for locking said bolt to one of said brackets for holding said bolt in a position in which said tray will be horizontal, comprising a tooth formed on one

of said brackets and engageable with a complementary cutout formed in the adjacent face of the head of said bolt, and a spring coaxially mounted on said bolt and operating between the other of said brackets and the nut of said bolt 5 for urging said bolt into a position in which said tooth will engage said cutout whereby said spring may be compressed by manually moving said bolt to disengage said cutout from said tooth to free said bolt so that said second means may 10 tilt said tray.

RAFAEL LAN.
